Application August 19, 1938, Serial No. 225,686

17 Claims. (Cl. 51—34)

The invention relates to honing machines, particularly for honing internal cylindrical bores.

One object of the invention is to provide a simple apparatus whereby the several bores of a cylinder may be brought to the same size within close limits. Another object of the invention is to provide apparatus for honing cylinder bores with provision for automatic adjustment of the honing tools. Another object of the invention is to provide an improved method for the continuous adjustment of radially expanding honing tools. Another object of the invention is to provide automatic adjustment means for honing tools capable of being applied to existing machines. Another object of the invention is to provide apparatus which takes the guess-work out of honing tool adjustment. Other objects will be in part obvious or in part pointed out hereinafter.

The invention accordingly consists in the features of construction, combinations of elements, and arrangements of parts, and in the several steps and relation and order of each of said steps to one or more of the others thereof, all as will be illustratively described herein, and the scope of the application of which will be indicated in the following claims.

In the accompanying drawings illustrating one of many possible embodiments of the mechanical features of this invention,

Figure 1 is a side elevation of a honing machine constructed in accordance with the invention, certain parts being shown in section;

Figure 2 is a horizontal sectional view taken on the line 2—2 of Figure 1;

Figure 3 is a horizontal sectional view taken on the line 3—3 of Figure 1;

Figure 4 is a pneumatic diagram;

Figure 5 is a front elevation of a portion of the machine shown in Figure 1, certain parts being shown in section;

Figure 6 is a vertical axial sectional view of a honing tool which is arranged to be automatically adjusted according to the invention;

Figure 7 is a horizontal sectional view taken on the line 7—7 of Figure 6.

The invention may be incorporated in a honing machine of the type described in U. S. Letters Patent No. 1,783,019 to Albert M. Johnson. In fact, machines already constructed according to this patent (hereinafter referred to as the Johnson patent) may be changed over with the addition of certain mechanisms herein described to operate automatically or semi-automatically according to the present invention. The invention is disclosed in connection with a honing tool, such

as shown in the patent to Fred M. Kern No. 1,927,-039 (hereinafter referred to as the Kern patent). However, the invention may readily be adapted to operate in connection with other types of honing tools.

As in the case of the Johnson patent, and referring now to Figure 1, the machine comprises a base 1 upon which is fixed an upright column 2 frontwardly provided with a pair of vertical slide-ways 3. A piece of work is shown supported on the base 1 comprising in the present instance a four-cylinder internal combustion motor block 6 clamped in any suitable manner, not shown, upon an adapter block 7 which rests upon a flat surface of the base 1.

Referring to Figures 1 and 5, mounted upon the upper end of the column 2 is a main housing 8 having a pair of upright auxiliary housings 9 and 10. The auxiliary housings 9 and 10 each support a vertically positioned spindle driving shaft 11. The spindle driving shafts 11 are journaled in guide sleeves 14 reciprocably mounted in the auxiliary housings 9 and 10. On the upper end of the housing 9 is a gear casing 9a while on the upper end of the housing 10 is a similar gear casing, not shown. By means of gearing contained within these gear casings and further gearing contained within the main housing 8 and the auxiliary housings 9 and 10, the spindle driving shafts 11 are rotated all at the same angular velocity. At the same time, owing to the fact that the shafts 11 are splined, as clearly shown in Figure 1, and fit in gear sleeves, not shown, the rotary drive to the spindles 11 in no wise interferes with their vertical reciprocatory movement. This driving mechanism together with clutch and brake device will be found more fully described in the Johnson patent. The Johnson patent also describes fluid pressure actuating mechanism for moving the guide sleeves in unison up and down. Controlling apparatus for the fluid pressure reciprocating mechanism is provided whereby, at the will of the operator, the sleeves 14 may be caused to descend, to reciprocate in a lower range, and to rise above this lower range at will. Such apparatus we shall not describe herein since reference may readily be made to the Johnson patent. Some of the controls described in Crompton's copending application Serial No. 219,988 filed July 19, 1938 may also be used if desired.

Still referring to Figures 1 and 5, suitably attached to the sleeves 14 is a head 20. This head moves up and down in unison with the sleeves 14 and journals a plurality of spindles 21 mounted in

parallel relation. By gearing in the head 20 which is fully disclosed in the Johnson patent referred to, all four of the spindles 21 are driven at the same speed and in the same direction, the 5 right-hand pair being driven by the right-hand spindle 11 and the left-hand pair being driven by the left-hand spindle 11.

Referring now to Figure 6, we provide a plurality of honing tools 25 which may be of substantially the same construction as illustrated and described by the Kern patent. As reference may be readily had to the Kern patent, we shall only briefly describe some of the major parts of the honing tool 25 herein. As shown, the tool includes a lower spindle 26 and an upper spindle 27. Each spindle 21 has a bayonet socket 30 at the lower end thereof which receives a trunnion pin 31 projecting through spherical members 29 located in the internal bore 22 of the spindle 20 21. The pin 31 also passes through the upper spindle 27 and thereby holds the entire honing tool 25 to the spindle 21, this construction constituting a universal joint.

The spindle 27 is connected to the spindle 26 by means of a universal joint 32. The spindle 26 supports an upper spider 33 and a lower spider 34, which spiders guide holders 35 and 36 supporting metal carriers 37 in which are set abrasive stones 38. The abrasive stones 38 which 30 may be made of any suitable abrasive material, such as alumina or silicon carbide bonded with organic or vitrified bond, are thus mounted for radial movement in the tool 25. Removable garter springs 40 fitting over projecting hooks 41 of 35 the metal members 37 bias the holders 35 and 36 and the abrasive members 38 inwardly and hold these parts in assembled relation.

The upper portion of the spindle 27 is threaded and thereon are a pair of nuts 47 and 48 which 40 are relatively movable for providing a locking engagement for longitudinally positioning a cam carrying collar 50 mounted on a sleeve portion 47a of the nut 47. Between the flange of the nut 47 and the collar 50 are a plurality of washers 49 for reducing the rotational friction between the members when adjustment is made. At the lower end of the collar 50 are formed a plurality of pairs of ears 51 between which extend pins 52 journalling cam levers 53. We form 45 these cam levers 53 with elongated upper ends 54 so that they may be operated from the top as well as from the bottom.

The lower ends of the cam levers 53 engage a conical cam surface 55 of a thrust collar 56, the 55 lower surface of which engages steel balls 57 mounted in a ball cage 58. The balls 57 rest on an adjustment collar 59 seating in spherical depressions 60 thereof which are shown in Figure 7. The adjustment collar 59 is internally threaded and mounted on the exteriorly threaded portion 60 of a sleeve 61 which is journaled on the unthreaded portion of the spindle 27. The sleeve 61 is an integral part of a housing 62 which encloses a spring cage 63 holding a powerful spring 64 under initial compression. A shoulder 65 of the housing 62 is positioned to engage the upper end of the spring 64, as clearly shown in Figure 6. The lower end of the cage 63 rests on a plurality of washers 66, the lower one of which engages a 65 pair of thrust rods 70 located in grooves in the spindle 26. These thrust rods 70 bear against an actuating member 71 having three sets of conical surfaces positioned to engage wedge portions on the holders 35.

75 By means of this construction, which is more

fully detailed in the Kern patent, whenever the cam levers 53 are compressed inwardly (there being usually three of such cam levers), the thrust collar 56 is depressed which forces downwardly the adjustment collar 59, thereby moving 5 downwardly the housing 62 which, through the spring 64, depresses the thrust rods 70 which moves downwardly the actuating member 71, thereby expanding the holders 35 and 36. The reacting thrust is, of course, taken through the 10 pins 52 to the collar 50 to the nut 47 to the spindle 27, thence through the universal joint 32 to the spindle 26, thence to the spiders 33 and 34 which hold the holders 35 and 36 from downward movement. The stones or abrasive sticks 38 are 15 directly expanded in this manner unless they are positively prevented from expanding by a pressure which will overcome the initial tension of the spring 64 backed up by the mechanical advantage inherent in the cone and wedge actuating means. The exact effective diameter of the sticks 38, however, is dependent entirely upon the adjustment of the collar 59. We provide ratchet teeth 75 on the periphery of the adjustment collar 59 for automatic actuation of this 20 collar automatically to adjust the several tools.

Before describing the features which are more especially our present invention, as conducive to a better understanding thereof, we will now mention a common manner of operating the 30 machine tool of the Johnson patent equipped with honing tools of the Kern patent. It has been customary to provide a set of sleeves just above the bores of the cylinder block being honed through which the honing tools pass and which 35 compress the cam levers 53 when the honing tools are down. In machine tools so operated, the hones are collapsed when the head 20 is up and are expanded by the action of these sleeves just after the tools 25 enter the several bores of the cylinder block being honed. At the end of a particular honing operation on a particular cylinder block, the operator has adjusted the collars 59 by an amount sufficient in his judgment to account for wear of the sticks 38 or to bring the bores of 40 the next cylinder block to the desired size. In tools so operated, however, cylinder bores of the cylinder blocks have varied in final diameter so that as many as five different sizes of pistons 45 have been provided in regular automobile production to match the different sized bores.

According to our present invention in one of its aspects, we provide two sleeves above each engine cylinder bore into the lower one of which we expand the hone when it is in its upper 55 position by compressing the cam levers 53 with the upper of such sleeves. We further cause an automatic device to move the adjustment collar 59 to expand the particular hone until substantial resistance is met with. Thereby the honing 60 tools are automatically set so that they will ultimately expand in the cylinder bores to the required or desired diameter and the adjustment is not dependent upon guess-work but is a pre-determined adjustment. Since the sleeves which 65 we provide may be slightly larger in diameter than the bores to be honed, we may thereby allow for wearing of the honing sticks during a particular honing operation. This reduces the variable to the difference in wear of the honing sticks 70 during successive operations, which is a much smaller quantity than the total amount of wear.

Referring again to Figure 1, we provide a plurality of metal sleeves 80 supported in a single bracket 81 slidably mounted for vertical adjust- 75

ment on the ways 3 and rigidly clamped in adjusted position in any suitable manner, as by means of bolts 82. In the present illustrative embodiment of the invention, in which there are 5 four bores in the cylinder block 6, there are four sleeves 80 spaced the same as the bores in the cylinder block. In accordance with considerations above mentioned, the internal diameter of the sleeves 80 is slightly larger than the ultimate 10 desired size of the work piece bores. In order that the cam levers 53 may readily enter the sleeves 80, and in order to avoid fracturing of the abrasive sticks or stones 38, the sleeves 80 are bell mouthed at both ends, as shown. 15

We further provide, as also shown in Figure 1, four sleeves 85 of internal diameter the same as the sleeves 80 and bell mouthed on the lower ends. These sleeves 85 are mounted in a bracket 86 which is slidably mounted on the ways 3 and 20 adapted to be clamped in any position of adjustment, as by means of bolts 87. Figure 1 shows the honing part of the tool 25 located in the sleeve 80 while the cam levers 53 are located in the sleeve 85. If then at this point the adjustment collar 59 be moved to eliminate any space between the spring 64 and the shoulder 65 and also any space between the sticks 38 and the sleeves 80, thereafter when the tool 25 is lowered 25 into the bore of the work piece 6, it will be expanded by engagement of the sleeve 80 with the cam levers 53 and, since the bore in the work piece 6 must be somewhat under size, the spring 64 will be slightly compressed within its cage 63 and later on, when the cage 63 contacts the 30 spring 64, the work piece will have been honed to predetermined size, which will be the same as the internal diameter of the sleeve 80 less wear of the abrasive sticks during that particular honing operation. Since the adjustment collar 40 59 may be easily turned with the fingers to take out backlash in the parts, or to compress a weak spring 90 (provided in the honing tool according to the Kern patent), but can only with great difficulty be moved to compress the powerful 45 spring 64, we provide resilient operating means to revolve the adjusting collar or collars 59 by engagement with the ratchet teeth 75, which is powerful enough to take out the backlash and compress the spring 90 but not powerful enough 50 to compress the spring 64 beyond its predetermined initial tension. Such apparatus in the present illustrative embodiment of our invention comprises multi-toothed pawls operated by cylinder and piston apparatus energized by pneumatic 55 or steam pressure.

Referring now to Figure 4 which, excepting for the pipe connections, is not wholly diagrammatic, we provide a plurality of cylinders 100, one for each honing tool 25, which would be four in the 60 present embodiment. These cylinders 100 may be mounted on a suitable ledge 101 provided on the inside of the column 2 and fastened to this ledge. But in the case of changing over old machines, these may be mounted in front of the 65 machine on a suitable stand or bracket. Each cylinder 100 is provided with a piston 102 mounted on a piston rod 103. The piston rods 103 project forwardly through cylinder heads 104 which, with rear cylinder heads 105, close the 70 ends of the cylinders 100. As shown in Figure 1, the piston rods 103 likewise project through holes formed in the front wall of the column 2.

We provide on the front of each piston rod 103 a multi-toothed pawl member 110. These may be in the form of bars with ratchet teeth. Each

multi-toothed pawl member 110 is pivotally mounted on its corresponding piston rod 103 so that it can move in a horizontal plane. Figure 4 gives approximately a plan view of the several cylinders 100, pistons 102, piston rods 103 and pawls 110. The articulation joints 111 are so formed that the pawls 110 cannot move in a counterclockwise direction beyond the positions shown in Figure 4 and also in Figure 1, but the joints permit movement of the pawls 110 in a 10 clockwise direction. We provide finger springs 112 bolted by bolts 113 to the piston rods 103 and engaging the pawl members 110 normally to hold the pawl members in the straight line position shown. These springs 112, however, permit the 15 pawl members 110 to swing backwardly for a limited distance, that is to say in a clockwise direction, Figure 4.

The cylinders 100 are so located that the pawl members 110 are in position to engage the ratchet 20 teeth 75 upon a forward movement of the pistons 102. We provide a pneumatic mechanism resiliently to urge the pistons 102 forwardly whenever the tail pieces 54 of the cam levers 53 engage the sleeves 85. Referring now to Figures 25 1, 3 and 4, we provide a valve block 120 secured to the column 2, adjustably if desired. We further provide a valve operating abutment 121 secured to the head 20. Referring to Figure 4, the valve block 120 has chambers 125, 126, 127 and 30 128. In the chambers 125 and 126 are conical seats to seat poppet valves 129 and 130. These valves 129 and 130 are normally maintained against their seats by means of springs 131 and 132. In the chamber 127 and 128 we provide 35 poppet valves 133 and 134. In the upper parts of the chambers 127 and 128 are conical seats to fit the valves 133 and 134 but springs 135 and 136 normally hold the valves 133 and 134 away from the seats in the chambers 127 and 128.

We provide a pipe 140 connected to a suitable source of pressure. While liquid pressure may be used, especially in connection with a relief valve, we prefer to use gas pressure because of resiliency of its action. In our preferred embodiment, we use air pressure. The pipe 140 leads to the upper end of valve chamber 125 and a branch 140a leads to the upper part of the valve chamber 127.

In the lower part of the chamber 127 is a port 141 connected by a pipe 142 to a throttle valve 143 connected by a pipe 144 to a pipe 145 having branches 145a leading to the front ends of the cylinders 100. Figure 4 indicates the parts prior to the time when the cam levers 53 enter the sleeves 85. In other words, Figure 4 is consistent with Figure 5. Under such conditions the pressure is not cut off by the poppet valve 133 and is maintained in the forward ends of the cylinders 100, thus holding the pistons 102 rearwardly in the cylinders, as shown. Branches 146a of a pipe 146 open the exhaust to the chamber 128 through a port 147 and whenever the poppet valve 134 is down, the port 147 is connected to an exhaust port 148 which is open to the atmosphere. 65

Whenever the head 20 is in its uppermost position, as shown in Figure 1, the abutment member 121 is in engagement with the valves 129 and 130 and these are consequently open. Coincidentally the valves 133 and 134 are closed, the 70 valve stems thereof being engaged respectively by plungers 150 and 151 carried by the abutment member 121 but backed up by springs 152 and 153. Under such conditions pressure is cut off from the pipe 142 and the exhaust through the

pipe 146 is likewise cut off. The valve 129 being in its upper position, connects the pressure to a port 155 which is connected by a pipe 156, throttle valve 157 and pipe 158 to the pipe 146. This 5 opens the pressure to the right-hand ends of the cylinders 100. Poppet valve 130 being up, connects an exhaust port 160 to a pipe 161 which is connected to the pipe 145. This allows the air 10 to exhaust from the front ends of the cylinders 100.

In operation this mechanism normally maintains the multi-toothed pawls 110 in their rearward positions, as indicated in Figure 4. Figure 1 shows the parts with the valves 133 and 134 15 closed and the valves 129 and 130 opened and the cam levers 53 in the sleeve 85. The pistons 102, therefore, have moved forwardly. In so doing, the multi-toothed pawl members 110 have engaged the teeth 75 and rotated the adjustment 20 collars 59. The action, however, is a resilient or non-positive one and some collars may have been rotated more than others. Whenever the head 20 moves downwardly, the pawls 110 are all of them retreated. Usually this action will not 25 occur until the adjustment collars 59 have moved below the multi-toothed pawl members 110, but at all events these pawl members may move in retrograde direction on the teeth 75 without effect on the adjustment since the pawl members 30 110 are mounted to swing outwardly. Furthermore, the balls 57 and seats 60 act to prevent any retrograde motion of the parts of the honing tool.

In operation the honing tools 25 are expanded 35 by the sleeves 85 to the same extent that they are expanded by the sleeves 80. But subsequent to a particular honing operation there will be a variable amount of slack to be taken up in each honing tool so that the next work piece may be 40 brought to the desired size. This adjustment is automatically effected by the non-positively operated multi-toothed pawls 110 which act automatically whenever the head 20 reaches its uppermost position.

45 It is preferred that when the multi-toothed pawls 110 are moved forwardly to engage the ratchet teeth 75, the honing tools 25 have ceased their rotation. In the machine of the Johnson patent referred to, the rotation can be stopped 50 manually. However, automatic apparatus automatically to stop the rotation of the honing tools when the head 20 rises is disclosed in the pending application Serial No. 219,988 previously referred to. In any event we prefer that the 55 multi-toothed pawl 110 be on that side of the ratchet teeth 75 which it is to operate so that rotation of the tool moves the teeth in the same direction that the pawl does. Under such circumstances, if there is slight residual rotation 60 to the tool when the pawl acts, this will not break any parts and nevertheless the pawl will perform the desired operation by reason of the fact that its linear velocity can readily be made greater than the peripheral velocity of the ratchet teeth 65 under such circumstances. For example, the operator has merely to adjust the throttle valve 157 until the pawls move fast enough to effect the adjustment under all conditions of operation.

According to certain of its aspects the invention 70 may be embodied in apparatus herein disclosed, omitting the cylinder-piston units 100, 102 with the pawls 110 and the valve mechanism described. Owing to the provision of the two sleeves 80 and 85 for each honing tool, the operator himself may more readily and accurately

adjust the honing tools after each honing operation and our invention is to be deemed to include this apparatus whether with or without the automatic ratchet adjustment.

It will thus be seen that there has been provided by this invention a method and apparatus in which the various objects hereinabove set forth together with many thoroughly practical advantages are successfully achieved. As many possible embodiments may be made of the above 10 invention and as many changes might be made in the embodiment above set forth, it is to be understood that all matter hereinbefore set forth or shown in the accompanying drawings is to be interpreted as illustrative and not in a limiting 15 sense.

We claim:

1. In apparatus of the class described, a honing tool, expandable carriers for honing sticks in said honing tool, cam levers to expand said carriers, a mounting for said honing tool permitting it to be moved rectilinearly, and a pair of sleeves to actuate said cam levers and expand said carriers spaced apart substantially the same distance as the cam levers are spaced from the carriers whereby one sleeve will compress the cam levers to expand the carriers in the other sleeve. 25

2. In honing apparatus, a rotatable honing tool, a mounting permitting said tool to be moved rectilinearly, a support for a work piece, a first 30 sleeve, a second sleeve, the two sleeves being in axial alignment with each other and with the honing tool, and the work holder being formed to hold a work piece with a bore in axial alignment with said sleeves and said honing tool, said tool having carriers for abrasive sticks in said honing tool mounted for expansion, and means including cam levers to expand said carriers and spaced in an axial direction on the honing tool some distance from the carriers, so that when the 40 cam levers enter the second sleeve the carriers are expanded in the first sleeve and when the cam levers enter the first sleeve the carriers are expanded in the work piece.

3. In apparatus as claimed in claim 2, the combination with the parts and features therein specified, of take-up adjustment means between the cam levers and the carriers whereby the parts may be adjusted for wear when the cam levers are in the second sleeve and the carriers are in 50 the first sleeve so that the carriers will expand to a given predetermined amount in the work piece when the cam levers are in the first sleeve.

4. In apparatus of the class described, a honing tool having a lower operating position and an upper remote position and mounted to move rectilinearly through such positions, means to rotate said honing tool, carriers for abrasive sticks in said honing tool mounted for radial movement, members and connections whereby to expand said 60 carriers when said members are actuated, means to actuate said members when said honing tool is in the remote position, means to adjust the connections at such moment whereby to predetermine the ultimate size of work piece bores, 65 and gauging means contacting the abrasive sticks when the honing tool is in the remote position to procure the adjustment to a given total expansion of the abrasive sticks.

5. In apparatus of the class described, the combination with a honing tool comprising spindle means, holders mounted for movement of expansion and contraction relative to said spindle means, abrasive sticks secured to said holders, cam levers mounted on said spindle means re- 70 75

- move from said holders, a thrust collar operated by said cam levers, and connections between the thrust collar and the holders including a nut and a screw for adjustment, of automatic means to move the nut at predetermined intervals.
6. In apparatus of the class described, the combination with a honing tool comprising spindle means, holders mounted for movement of expansion and contraction relative to said spindle means, abrasive sticks secured to said holders, cam levers mounted on said spindle means remote from said holders, a thrust collar operated by said cam levers, and connections between the thrust collar and the holders including a nut and a screw for adjustment, of pawl and ratchet means to rotate the nut and piston and cylinder means to move the pawl at predetermined intervals.
7. In apparatus of the class described, the combination with a honing tool comprising spindle means, holders mounted for movement of expansion and contraction relative to said spindle means, abrasive sticks secured to said holders, cam levers mounted on said spindle means remote from said holders, a thrust collar operated by said cam levers, and connections between the thrust collar and the holders including a nut and a screw for adjustment, of a pair of sleeves in axial alignment spaced so that the cam levers may enter one sleeve while the holders and abrasive sticks are in the other sleeve and automatic means to rotate the nut at such stage with a resilient pressure.
8. In apparatus of the class described, a honing head, a mounting permitting said honing head to be moved rectilinearly, a plurality of spindles in parallel relation carried by said honing head, the axes of the spindles being parallel to the line of movement of the head and the spindles being mounted for rotation, a honing tool carried at the remote end of each spindle and each honing tool comprising holders for abrasive sticks, mountings for the holders holding the sticks in parallel relation and permitting expansion and contraction, cam levers remote from the holders, an adjustment ring, a screw threaded member upon which said adjustment ring is mounted, connections from the cam levers through the adjustment ring to the holders whereby when the cam levers are compressed the holders are expanded, a set of sleeves remote from the head whose axes are all parallel to each other and to the spindles and are in axial alignment with the spindles and of a size to actuate the cam levers to compress them when the holders are in work piece bores to expand the abrasive sticks to effect a honing operation, and a second set of sleeves in axial alignment with the first set, of the same size and between the first set and the head whereby to actuate the cam levers and expand the holders, pressing the sticks against the walls of the first sleeves.
9. In apparatus as claimed in claim 8, the combination with the parts and features therein specified, of automatic means to operate the adjustment ring when the cam levers are in one set of sleeves and the holders are in the other set of sleeves to take up all the back play at such time.
10. In apparatus as claimed in claim 8, the combination with the parts and features therein specified, of ratchet teeth on the adjustment rings, a plurality of pawls to actuate the ratchet teeth, and resilient means to actuate the pawls.
11. In apparatus as claimed in claim 8, the combination with the parts and features there-
- in specified, of a plurality of cylinders and pistons, a source of fluid under pressure, valve means to connect the several cylinders to the pressure fluid, said valve means being automatically operated when cam levers are in the sleeves nearest the head, and devices connected to the pistons to operate the adjustment rings at such time.
12. In apparatus of the class described, the combination with a spindle mounted for rotation and for rectilinear movement to advance, withdraw and reciprocate, a honing tool mounted at the end of said spindle comprising radially mounted parallel holders for abrasive sticks, apparatus to expand said holders, and adjustable connections between the holders and the apparatus, of means to actuate the apparatus to expand the holders when the spindle is reciprocating, and additional means to actuate the apparatus to expand the holders when the spindle is withdrawn, said two last named means permitting the holders to be contracted when the spindle is advancing and withdrawing, the entire apparatus including gauging means to gauge the expansion of the abrasive sticks when the spindle is withdrawn whereby to set the apparatus to bring a work piece bore to desired size within the limits of variability of wear of the honing sticks in a particular honing operation.
13. In apparatus of the class described, a honing head, a plurality of parallel spindles mounted in said honing head, means to rotate said spindles, means to move said head rectilinearly, a honing tool mounted in each spindle and including holding members for abrasive sticks mounted for expansion and contraction in parallel relation, actuating devices, adjustable connections from said actuating devices to said holders whereby to expand said sticks, means for actuating all of the actuating devices when the honing tools are outside of the bores of a work piece, means for gauging the amount of expansion of the abrasive sticks at such time, and means for adjusting the adjustable connections at such time to expand each of the honing tools to a predetermined amount, the apparatus including also means for actuating the actuating devices when the honing tools are in the bores of a work piece whereby the adjustment with the tools outside the work piece gauges the tools for bringing the bores to a desired size.
14. Apparatus of the class described comprising a honing head mounted for rectilinear movement, a plurality of spindles carried in parallel relation by said honing head and mounted for rotation, honing tools carried by said spindles, said honing tools being capable of expansion and contraction, adjustable devices to expand said honing tools whereby the amount of expansion of the tools may be adjusted, a plurality of non-positive automatically actuated means to adjust the adjustable devices, and gauging means to gauge the amount of adjustment at such time whereby to bring all of the hones to a given setting relative to their effective diameter in view of wear on the abrasive sticks.
15. In apparatus of the class described, a honing tool having a lower operating position and an upper remote position and mounted to move rectilinearly through such positions, means to rotate said honing tool, carriers for abrasive sticks in said honing tool mounted for radial movement, members and adjustable connections whereby to expand said carriers when said members are actuated, means to actuate said members when said honing tool is in the remote po-

sition, and gauging means to measure the expansion of the carriers by contact with the abrasive sticks whereby the connections may be adjusted to cause a given expansion of the sticks 5 to result from a given actuation of the members.

16. In apparatus of the class described, a honing head mounted to move rectilinearly, a plurality of spindles mounted in said head, means to 10 rotate all of the spindles, honing tools carried by the spindles, sleeves approximately the size of work piece bores to limit the expansion of the honing tools, devices on the spindles which when actuated expand the honing tools, take-up adjustments for said devices, means to actuate the 15 devices, and means to actuate the take-up adjustments, said last two means being operated when the honing tools are in the sleeves whereby to expand the honing tools to a given amount 20 to predetermine the diameter of work piece bores.

17. In apparatus of the class described, a honing tool comprising a plurality of abrasive sticks mounted in parallel arrangement to define a cylinder, means mounting the sticks permitting radial movement, adjustable means to move the sticks radially, a spindle for the honing tool, means to rotate the spindle, means to reciprocate the spindle, a non-positive actuated device to adjust the means to move the sticks radially, actuating means for the adjustable means, and 10 a gauge for the honing tool whereby the actuating means expands the tool and the gauge acts as a stop while the non-positive means moves the adjustment to cause the sticks to contact the gauge, thus setting the apparatus for honing a 15 bore to within precision limits despite wear on the sticks.
